SUBMARINE CABLE SIGNALING SYSTEM

Bertram S. Diamond, St. Johns, Newfoundland,
assignor to Commercial Cable Company, New
York, N. Y., a corporation of New York

Application July 10, 1941, Serial No. 401,807

8 Claims. (Cl. 178—63)

This invention relates to submarine cable signaling systems.

It is known that the attenuation of sinusoidal alternating currents transmitted over an ocean cable varies with the frequency of the current. The phase of the received current with respect to that at the sending end also varies with the frequency of the current.

As cable Morse signal currents contain alternating currents of many frequencies, the effect of the attenuation and phase shift of these components is to cause a great distortion of the received signaling currents.

This distortion is partially overcome by the use of shaping networks at the sending end and at the receiving end of the cable circuit in a manner well known in the art of cable operation.

It has been found very difficult, however, to carry this correction beyond a certain point by means of available electrical networks and the remaining distortion is the principal cause in limiting the speed of operation of cable circuits. Certain of the shorter signal combinations are among the most important as regards the application of pre-distortion to further reduce distortion at the receiving end. Among these are the combinations for A, N, D, G, W, U, and a succession of alternate E's and T's.

Signals received over a long cable may be considered as being formed by a number of sinusoidal components. For convenience, definite sequences of these signal combinations may be studied which, being then periodic, can be analyzed by Fourier's Theorem. The analysis shows that each of the various wave forms for the signal combinations listed above has two essential components, namely, a fundamental frequency and a harmonic, and that signal distortion is largely due to partial suppression and phase shift of harmonics, particularly such harmonics as $2n/3$, $3n/4$, $3n/5$, $4n/7$, $5n/7$, etc., where n is the rate of speed in signaling elements.

The object of the present invention is directed towards making a further improvement in correcting distortion by pre-distorting the signal currents at the sending end in a sense opposite to that which is caused by their transmission over the cable. Thus, if the currents of various essential frequencies, listed above, which form the cable signals when combined, were transmitted with their respective amplitudes such that each would have approximately the same amplitude on the receiving instrument as at the sending end and, at the same time, a phase correction was applied to each component that would counteract the phase displacement that occurs in transmission, the received signals would be free from distortion.

The invention will now be described with the aid of the accompanying drawings, of which,

Fig. 1 is a schematic showing of the circuits of one embodiment of the invention.

Fig. 2 shows the circuit arrangement for a modification of the invention.

Fig. 3 is a group of curves illustrating signals received from a circuit according to the present invention.

Fig. 4 is a group of signal curves from an ordinary transmitting circuit.

Fig. 5 shows the effect of transients on a wave form, while Fig. 6 shows the same wave form as received from a transmitter circuit according to the present invention.

Fig. 7 shows curves of groups of three reversals and the curbing impulses transmitted therewith.

Referring now to Fig. 1 of the drawings.

The contacts of a tape controlled transmitter are shown schematically in the drawings. The mechanical details of the transmitter being well known are omitted, but it is to be understood that the mechanism is of the type, in the present embodiment which sends "block" signals, rather than "beat" signals, that is to say, that instead of sending out four beat impulses for the letter H, one block impulse is sent of a duration equal to the time of sending the four beat signals. The transmitter has a dot contact lever 2 and a dash contact lever 3 cooperating with fixed contacts 4 and 5 respectively. The operation of these contacts is controlled by a tape and tape feeding mechanism and cooperating pecker rods attached to said contact levers which sense perforations in a tape. This mechanism is well known and not shown. An adjustable cam 6 turning in fixed relation to a member, not shown, for reciprocating the pecker rods, engages cam arm 7 and closes contacts 8 and 9 once each revolution.

When the dot pecker rod enters a perforation in the tape, contacts 2 and 4 close, and positive potential from sources 10 and 11 flows through a winding 12 of dot locking relay 14 and 13 of dot pulse transmitting relay 15 back to negative potential on the pecker contacts.

When the dash pecker rod enters a perforation, a similar pair of circuits is closed, from positive potential sources 17 and 18 through windings 19 and 20 respectively of dash locking relay 21 and dash pulse transmitting relay 22.

The closing of either circuit just described will cause the operation of the particular relays included therein. In the present case, windings 25 and 26 of the dot and dash locking relays and 27 and 33 of the respective pulse transmitting relays are constantly energized by a light potential sufficient to return the armatures to the left or spacing side whenever the other windings are deenergized.

When either dot locking relay 14 or dash locking relay 21 is operated, the tongue thereof moves

from the left or spacing contact **S** to the right or marking contact **M** where it remains until the current is cut off by the opening of the corresponding pecker contact. The spacing contact of the dot relay is connected through winding **28** thereof and through winding **29** of a dot signal transmitting relay **30**. Marking contact **M** is connected through winding **32** in series with winding **23** of dot signal transmitting relay **30**. Cam contact **8** is connected to both of the circuits just described at junction point **34**.

The windings of relays **21** and **31** are interconnected in a similar manner. Dash locking relay **21** has its contact **S** connected through winding **37** and winding **38** of relay **31** to the tongue of relay **14**. Marking contact **M** of relay **21** is connected through winding **40** thereof and winding **41** of relay **31** to the tongue of dot locking relay **14**. The tongue of relay **21** is connected to a source of positive potential. Marking contacts **M** of signal transmitting relays **30** and **31** are connected through suitable resistances **R6** and **R9** to the positive pole of a source of potential **45**, while the corresponding spacing contacts are similarly connected to the negative pole thereof through resistances **R5** and **R7**.

Tongue **46** of dot signal transmitting relay is connected to ground and also through condenser **48** to the apex **51** of a conventional cable bridge duplex. Tongue **47** is connected through winding **49** of transformer **50** to apex **51**.

One terminal of winding **52** of transformer **50** is connected through variable condenser **53** to tongue **54** of relay **15**, while the opposite terminal is connected through variable resistance **55**, for the purpose of controlling the amplitude of signals, to tongue **56** of relay **22**. Spacing contacts of relays **15** and **22** are connected through suitable resistances **R11** and **R13** to the negative pole of source of potential **57**, while the marking contacts thereof are connected in like manner to the positive pole of said source.

The circuit from the transmitter including dot locking relay **14**, dash locking relay **21**, signal transmitting relays **30** and **31** up to and including the actual cable circuit, with the exception of the transformer circuit, is well known and operates in the usual manner. Closing of a dot or dash transmitter contact operates either the dot or dash locking relay. The subsequent closing of cam contacts **8** and **9** operates a corresponding signal transmitting relay over a circuit prepared by the operation of either dot or dash locking relays. The signal transmitting relays being polarized remain in their last operated position until the cam contacts **8** and **9** again close, and from their tongues are sent the various three element signal combinations of cable Morse, composed of dot, dash and zero elements. When a zero signal follows a dot or dash signal the locking relays are not operated, their tongues having both been restored to their spacing contacts by the weak current through the windings **25** and **26**, and the closing of cam contacts **8** and **9** causes the previously operated dot or dash signal transmitting relay tongue to return to its spacing contact and thus send a zero signal to the cable.

The secondary **49** of transformer **50**, however, is included in the output circuit from the signal transmitting relays and the primary **52** thereof is energized by current from potential source **57** as pulse transmitting relays **15** and **22** are operated. It will be noted that these relays operate at the same time as dot and dash locking relays **14** and

21, which is to say, in advance of relays **30** and **31**.

With the operation of, for instance, dot signal relay **30**, a dot signal is sent through the secondary of the transformer into the cable. This is combined with that already being sent from the transformer through the slightly previous operation of the dot pulse transmitting relay **15** which was operated directly from the same closing of the dot contacts **2** and **4** of the cable transmitter. As previously stated, the transmitter sends out block signals, and relay **15** will remain on its marking contact until dot transmitter contacts **2** and **4** again open.

Condenser **53** is inserted in the transformer input circuit, so that this circuit may be tuned to any desired range of frequencies and resistance **55** is inserted in order to control the amplitude and the sharpness of the tuning. With proper values of inductance in the transformer primary and secondary respectively, and with the proper ratio of the effective E. M. F. developed across the transformer secondary to that of the signaling battery on the signal transmitting relays, the amplitude of the higher frequencies may be greatly increased in relation to that of the lower frequencies with the result that signal shape at high speed constants is considerably improved at the receiving end and higher rates of speed are thus made possible. The effect of this pre-distortion by the use of the circuits of Fig. 1 is shown by the signals of Fig. 3. These signals should be compared with those of Fig. 4 which were sent without pre-distortion.

The insertion of inductance in the transmission mesh has the effect of changing the phase relationships between the various frequency components and the signals, tending to retard the higher frequencies relatively. To compensate for this, the signal transmitting relays should be retarded in order to obtain the best results at high speed constants, the actual phase difference between the pulse transmitting relays and the signal transmitting relays which will give best results depend on the various circuit constants. The retardation of the signal transmitting relays may be accomplished by any well known method, for example, the adjustable cam and contact arrangement shown in the present embodiment, and/or the insertion of a relay in the cam contact circuit.

Condenser **48** is for the purpose of by-passing those higher harmonics which are imperceptible at the receiving end and play no part in the formation of signals but are troublesome in obtaining and maintaining good duplex balance conditions.

Variation in the rate of attenuation is not, however, the only serious source of distortion. It has been found that the effect of transients is frequently very difficult to eliminate, especially at high speed constants. Possibly the most obvious example of this is apparent in a train of reversals which, when applied to a cable, has an arrival curve at the receiving end consisting of three components, a transient, a periodic, and a second transient, the first transient being of the same polarity as the first element in the train, and the second transient being of the same polarity as the last element of the train. The relative amplitudes of transient and periodic movements before entering the receiving network will vary according to the rate of speed, KR of the cable, and nature of the sending network.

Fig. 5 shows the effect of transients on trains of reversals, each of four cycles, as received at a high speed constant from a standard transmission network. It will be observed that the first and last elements are thicker and have greater amplitude than the inside elements.

Fig. 6 shows trains of reversals at the same speed and with the same receiving conditions but with the transmitting circuit of Fig. 1. This circuit as well as the modification thereof described below provides shorter pulses of opposite polarity to that of the signaling element at the beginning and ending respectively of each group of signaling elements, when the transformer secondary is connected so that it sends a pulse in the proper sense with respect to the signal from the Signal transmitting relays. These short impulses, which may be termed "curbing impulses," curb the transients, and reduce considerably distortion from this cause. This is shown in Fig. 7 which represents the sending end pulses of a train of reversals. The train of reversals in this case is one of three complete cycles.

Another embodiment of the invention is shown in Fig. 2 in which two tuned transmitting units are used in addition to the normal signal transmitting relays. The relays are operated in the same manner as the corresponding relays of Fig. 1 but in this case two pairs of pulse transmitting relays are employed, the operating windings thereof (not shown) being controlled directly from the transmitter contacts. In this case the primary of one transformer 66 or 67 may be tuned to the band of frequencies between, say, $3n/5$ and $5n/6$, while the primary of the other transformer may be tuned to the band of frequencies between, say, $2n/5$ and $5n/7$. Or one may be broadly tuned to the higher frequency band while the other may be tuned as narrowly as may be found practicable on the band between, say $3n/5$ and $5n/6$.

While the present invention has been described in connection with cable terminal equipment it will be understood that the invention may be applied at intermediate transmitting points, i. e., cable repeaters, particularly of the regenerative type, where according to well known practice transmission is effected from rotary distributors. Furthermore it will be understood that the invention may be used for the transmission of signals other than cable Morse signals, for example, signals of the kind used in the printing telegraph art.

What is claimed is:

1. In a cable system, a signaling device, a transmitter for transmitting signals under the control thereof, an output circuit for said transmitter, means for keeping said output circuit in the rhythm of said signals, means for deriving a predetermined band of harmonics of a fundamental frequency at which said signaling device is operated, and means for impressing said harmonics upon said output circuit whereby said signals and said harmonics are combined in said output circuit.

2. In a cable system, a signaling device, a transmitter for transmitting signals under the control thereof, an output circuit for said transmitter, means for keying said output circuit in the rhythm of said signals, means for deriving a predetermined band of harmonics of a fundamental frequency at which said signaling device is operated, and means for impressing said harmonics upon said output circuit in a predetermined phase relationship with respect to said signals in said output circuit whereby retardation

of the high frequency characteristics of the composite signal by the cable is compensated.

3. In a cable system, a signaling device, a transmitter for transmitting signals under the control thereof, an output circuit for said transmitter, means for keying said output circuit in the rhythm of said signals, a tuned circuit controlled by said signaling device for generating a predetermined band of harmonics of a fundamental frequency at which said signaling device is operated, and a transformer having one winding in said output circuit and another winding in said tuned circuit.

4. A cable system according to claim 3, wherein a variable resistance is provided in said tuned circuit for controlling the amplitude of the harmonics generated therein.

5. A cable system according to claim 3, wherein a variable reactance is included in said circuit for tuning said circuit to any desired range of frequencies.

6. In a cable system, a keying device, a signal transmitting relay under the control of said keying device and having contacts for controlling a signal transmitting circuit, a pulse transmitting relay having an energizing circuit controlled by said keying device, a circuit including a source of potential, means for tuning said last-mentioned circuit to a predetermined band of harmonics of a fundamental frequency at which said keying device is operated, contacts controlled by said pulse transmitting relay for opening and closing said tuned circuit in the rhythm of the transmitted signals, and a transformer having one winding in said signal transmitting circuit and another winding in said tuned circuit.

7. In a cable signaling system for transmitting block signals, a keying device comprising dot and dash contacts, dot and dash locking relays, dot and dash signal transmitting relays, and dot and dash pulse transmitting relays, circuits controlled by said dot and dash contacts for operating said locking relays and said pulse transmitting relays, circuits controlled by contacts of said locking relays for operating said signal transmitting relays, a source of potential contacts associated with said signal transmitting relays for applying negative, positive, and zero potential conditions to said signal transmitting circuit, a circuit tuned to a band of harmonics of a fundamental frequency of the keying signals, contacts controlled by said pulse transmitting relays for connecting a source of potential to said tuned circuit, and a transformer having one winding connected in said tuned circuit and another winding connected in said signal transmitting circuit.

8. In a cable system, a signaling device, a transmitter for transmitting signals under the control thereof, an output circuit for said transmitter, a tuned circuit controlled by said signaling device for generating a predetermined band of harmonics of a fundamental frequency at which said signaling device is operated, a further tuned circuit controlled by said signaling device for generating a different predetermined band of harmonics of said fundamental frequency, contacts in said tuned circuits for opening and closing said tuned circuits in the rhythm of the signals, a first transformer having one winding in said output circuit and another winding in said first-mentioned tuned circuit and a second transformer having one winding in said output circuit and another winding in said second-mentioned tuned circuit.

CERTIFICATE OF CORRECTION.

Patent No. 2,328,789.

September 7, 1943.

BERTRAM S. DIAMOND.

It is hereby certified that error appears in the printed specification of the above numbered patent requiring correction as follows: Page 3, first column, line 56, claim 1, for "keeping" read --keying--; and that the said Letters Patent should be read with this correction therein that the same may conform to the record of the case in the Patent Office.

Signed and sealed this 7th day of December, A. D. 1943.
